DESIGN FOR A LIGHTING FIXTURE

Edwin F. Guth, Florissant, and Ervin C. Koegel,
St. Louis, Mo., assignors to The Edwin F. Guth
Company, St. Louis, Mo., a corporation of Mis-
souri

Application October 6, 1947, Serial No. 141,764

Term of patent 14 years

(Cl. D48—23)

To all whom it may concern:

Be it known that we, Edwin F. Guth and Ervin C. Koegel, citizens of the United States and residents of Florissant, St. Louis County, Missouri, and St. Louis, Missouri, respectively, have invented a new, original, and ornamental Design for Lighting Fixture, of which the following is a specification, reference being had to the accompanying drawing, forming part thereof, in which

Fig. 1 is a top plan of the lighting fixture showing our new design;

Fig. 2 is a bottom plan;

Fig. 3 is a side elevation; and

Fig. 4 is an end elevation.

We claim:

The ornamental design for a lighting fixture, substantially as shown.

EDWIN F. GUTH.
ERVIN C. KOEGEL.
